(57) **CLAIM**

We claim, the ornamental design for a display for a measurement device, as shown and described.

DESCRIPTION

FIG. 1 is a perspective view of a first embodiment of the invention;

FIG. 2 is a front plan view of the embodiment of FIG. 1;

FIG. 3 is a rear plan view of the embodiment of FIG. 1;
FIG. 4 is a first side plan view of the embodiment of FIG. 1;
FIG. 5 is a second side plan view of the embodiment of FIG. 1;

FIG. 6 is a top plan view of the embodiment of FIG. 1;
FIG. 7 is a bottom plan view of the embodiment of FIG. 1;
FIG. 8 is a perspective view of a second embodiment of the invention;

FIG. 9 is a front plan view of the embodiment of FIG. 8;
FIG. 10 is a rear plan view of the embodiment of FIG. 8;
FIG. 11 is a first side plan view of the embodiment of FIG. 8;
FIG. 12 is a second side plan view of the embodiment of FIG. 8;

FIG. 13 is a top plan view of the embodiment of FIG. 8;
FIG. 14 is a bottom plan view of the embodiment of FIG. 8;
FIG. 15 is a perspective view of a third embodiment of the invention;

FIG. 16 is a front plan view of the embodiment of FIG. 15, the rear plan view being the same as FIG. 10;
FIG. 17 is a first side plan view of the embodiment of FIG. 15;
FIG. 18 is a second side plan view of the embodiment of FIG. 15;

FIG. 19 is a top plan view of the embodiment of FIG. 15; and,
FIG. 20 is a bottom plan view of the embodiment of FIG. 15.
The dash-dot lines shown in FIG. 1-FIG. 2, and FIG. 6 indicate a screen having an indefinite size, the display for a measurement device according to the claimed design may have any size screen.

The phantom lines shown in FIG. 1-FIG. 20 are environmental and not part of the claimed design.

The color and shading of the display for a measurement device forms no part of the claimed design, the display for a measurement device according to the claimed design may be any color or combination of colors.

The surface treatment of the display for a measurement device forms no part of the claimed design, the display for a measurement device of the claimed design may have any surface treatment.

References to “side”, “top”, “front”, “rear” and “bottom” in the figure descriptions are not meant to require certain in-use orientation; a display for a measurement device according to the claimed design may be used in any orientation.
